UNITED STATES PATENT OFFICE.

JAMES C. WOODSON, OF MANSFIELD, OHIO, ASSIGNOR TO WESTINGHOUSE ELECTRIC PRODUCTS COMPANY, A CORPORATION OF MICHIGAN.

TUBING-HEAD HEATER.

Application filed November 18, 1921. Serial No. 515,687.

To all whom it may concern:

Be it known that I, JAMES C. WOODSON, a citizen of the United States, and a resident of Mansfield, in the county of Rich-
5 land and State of Ohio, have invented a new and useful Improvement in Tubing-Head Heaters, of which the following is a specification.

My invention relates to electrically heated
10 apparatus and particularly to electric heating units for the die blocks of tubing machines, and it has for its object to provide a relatively simple and compact heating unit which may be quickly mounted on, and
15 removed from, the head of a tubing machine of standard design.

In practising my invention, I provide a two-part annular casing having an open inner face and place therein a plurality of refractory resistor members each of which is provided with a plurality of open grooves adjacent the inner face thereof. I provide a resistor member located in the grooves and I provide also a terminal block 25 located in the annular casing and a cover member therefor. Means are provided to permit of mounting the heating unit on the head of the tubing machine.

In the drawings,
30 Figure 1 is a view, in side elevation, of a tubing machine upon the head of which is mounted a device embodying my invention;

Fig. 2 is a top plan view, of a device embodying my invention, portion being cut away, and

Fig. 3 is a view, in diametral cross section, of the device embodying my invention, taken on the line III-III of Fig. 2.

40 A commercial type of tubing machine is illustrated in Fig. 1 and designated by the numeral 10. A means for operating the machine may comprise an electric motor 11 suitably connected thereto. As such a machine is a commercial device and specifically constitutes no part of my invention, it is not herein described in detail and is illustrated only in order to show the mounting of my improved heating unit, designated 45 generally by the numeral 12, upon and surrounding the end of the head of the machine.

The heating unit 12 comprises two co-operating annular metal members 13 and 50 14, which are both of substantially L-shape

in cross section, each with a relatively small inturned flange portion 15 at the inner face. Lugs 16 and 17 are secured respectively against the members 13 and 14 in oppositely spaced relation to permit of clamping the 60 lugs 16 and 17 and, consequently, the members 13 and 14 in proper operative position by means of a screw bolt 18 and a nut 19.

A plurality of refractory resistor-supporting members 21 of substantially trapezoidal contour are placed within the annular space provided between the members 13 and 14. The peripheral width of the outer face of the members 21 is such 70 that a suitable number of the members 21 and a terminal block 22 fit into the annular periphery of the casing 12, an opening 23 being provided in the periphery of the casing through which a shoulder portion 24 75 of the terminal block extends. A plurality of open grooves 25 is provided in each of the members 21, the grooves being adjacent the inner surface of each of the supporting members and having overhanging walls so 80 that a helically wound resistor member 26 may be threaded into the grooves 25 of the members 21 and be retained therein, while permitting of radiating therefrom a relatively large proportion of heat generated. 85

The ends of the resistor member 26 may be suitably clamped on a terminal block 22 by means of screw bolts 27, having a plurality of nuts 28 mounted thereon to permit of connecting thereto a plurality of 90 supply-circuit conductors 29 which may be connected directly to a supply circuit (not shown) or, more usually, to controlling devices, such as a switch (not shown).

95 A cover member 31 may be secured against the casing 12 in such position as to cover the terminal block and the outer end of the bolts 27. Insulating bushings 32 may be located in the cover member 31 to suitably insulate the conductors 29 from 100 the metallic cover member 31.

A reflecting member 33 is mounted on the outer surface of the heating unit 12, being secured thereto by means of a plurality of screws 34. The reflecting member 105 33 is of substantially convex form, the concave surface thereof being so located as to constitute the outer surface, and the inner surface being suitably polished to effect the reflection of a large portion of the heat 110.

generated and radiated thereagainst. A central opening 35 is provided in the reflector 33 through which the finished tubing may pass.

5 A plurality of lugs 36 are secured to the casing, being located on diametrically alined points, and are each provided with an opening 37 therethrough to permit of securing the heating unit against the machine 10 10 by means of bolts 38.

A heating unit, constructed as hereinbefore described, may be quickly mounted in its proper operative position on the head of a tubing machine to maintain the head 15 and the die blocks at a desired temperature and may also be quickly removed therefrom if desired and be quickly disassembled to permit of repair should this become necessary. The reflector member is effective to 20 reduce the amount of heat which is radiated by the resistor away from the head of the machine and to reflect a relatively large portion of the heat radiated against its inner surface back against the head of the 25 tubing machine.

Various modifications may be made in the device embodying my invention without departing from the spirit and scope thereof, and I desire that only such limitations shall 30 be placed thereon as are imposed by the prior art or are specifically set forth in the appended claims.

I claim as my invention:—

1. In an electric heater, in combination, 35 a substantially circular casing having an open inner surface, a refractory resistor-supporting means in said casing, a resistor located in said supporting means and a reflector secured to one end surface of the said casing and having a central aperture.

2. In an electric heater, in combination, a substantially circular casing having an open inner surface, a plurality of refractory resistor-supporting members located in said casing, each of said supporting members having a plurality of grooves on the inner surface thereof, a resistor member located

in said grooves and a reflector secured to one end surface of the said casing and having a central aperture.

3. In an electrically heated device for maintaining a predetermined temperature at the end of a tubing-machine head, in combination, a substantially circular metallic casing having an open inner surface, 55 a plurality of refractory resistor-supporting members located in side-by-side relation in said casing, each of said supporting members having a plurality of grooves extending laterally therethrough on the inner surface thereof, a helically wound resistor-member extending through said grooves, a terminal block in said casing and extending outwardly therefrom, terminals mounted in said block, a cover member for said 60 terminals, a reflector partly enclosing the outer lateral surface of said casing and means for securing said casing against said tubing-machine head.

4. In an electric heating device for maintaining a predetermined temperature at the end of a tubing-machine head, in combination, a separable two-part, substantially circular casing having an open inner surface, 70 a plurality of laterally-grooved refractory resistor-supporting members located in said casing, a terminal block also in said casing and covering, in combination with the supporting members, substantially all of the periphery of said casing, a flexible resistor-member supported by said refractory supporting members, terminals mounted in said terminal block and extending beyond the outer periphery of said casing, 75 a cover member for said terminals secured to said casing, means for securing said casing against said tubing-machine head and a reflector secured to said casing and having a central aperture.

In testimony whereof, I have hereunto 80 subscribed my name this 2nd day of November, 1921.

JAMES C. WOODSON.
